UNITED STATES PATENT OFFICE.

AUGUSTIN J. CHEVRETTÉ, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

TERRY-PILE-FABRIC LOOM.

Application filed December 30, 1924. Serial No. 758,920.

My present invention relates to improvements in terry pile fabric looms and it is the general object of my invention to form terry piles by means which give the cloth 5 a positive back and forth motion with respect to the forward position of a lay moving through a fixed range of action.

My invention relates more particularly to that type of loom wherein very high pile 10 is produced and wherein the formation of terry is accomplished by moving the fell of the cloth rearwardly toward the loom reed periodically on the pile forming pick after which the fell is moved forwardly 15 again to permit the laying of the picks which form the pile.

Another object of my invention is to provide adjustable means for forming pile of varying heights wherein the means are 20 actuated positively in both directions for all adjustments.

It is a further object of my invention to provide a positive lock for holding the cloth in rearward position at the time a heading 25 is being woven.

With these and other objects in view which will appear as the description proceeds, my invention resides in the combination and arrangement of parts hereinafter 30 described and set forth in the claims.

In the accompanying drawings, wherein I have shown two forms of my invention,

Fig. 1 is a side elevation of a loom having my invention applied thereto,

Fig. 2 is a detailed horizontal section on line 2—2 of Fig. 1,

Figs. 3, 4, 5, and 6 are diagrammatic views showing the successive positions of the cloth and lay during a complete cycle,

Fig. 7 is a detail elevation of the cam by means of which the fell of the cloth is moved positively in both directions, and

Fig. 8 is an enlarged end view of the rear whip rolls shown in Fig. 1.

My present invention relates more particularly to improvements in the devices for moving the cloth and comprises a loom frame 10 having a rocker shaft 11 upon which is pivotally mounted a lay 12 actuated by a suitably driven connector 13. The lay is provided with a fixed reed 14 which moves back and forth in a fixed range of action. The loom is provided with a lower ground warp beam 15 and an upper terry

warp beam 16 which are suitably mounted 55 to deliver warp in the required amounts. Ground warp W^g is lead upwardly from the beam 15 over a whip roll 17, forwardly to a guide bar 18, and downwardly to the take-up 19 from which the cloth may pass in any 60 desired manner to the cloth roll 20. The whip roll 17 is supported on an arm 21 which is pivotally mounted about a horizontal shaft 22, said arm being rigid with a 65 depending arm 23 connected to a forwardly extending link 24. The guide bar 18 is mounted on an arm 25 upstanding from a lever 26 which is fixed to a shaft 22'. The lower end of the lever 26 is connected to a rearwardly extending link 27 by means of 70 which said lever is rocked.

The connectors 24 and 27 are pivotally attached as at 28 to an upstanding lever 29 loose on a shaft 30 supported on one of the cross girts 31 of the loom. Said lever 29 75 has formed thereon upper and lower arms 32 and 33, respectively, which are spaced sufficiently to receive therebetween a lug 34 extending laterally from a lever 35 also loosely mounted on said shaft 30. Upper 80 and lower set screws 32^a and 33^a, respectively, engage opposite sides of the lug 34 to cause said lever 29 to move when the lever 35 is actuated.

The rear end of arm 35 has rotatably mounted thereon a roll 36 which is positioned for engagement with a cam 37 normally rotating in the direction of arrow A, Fig. 1, and secured to stub shaft 38 which rotates in fixed bearings 39. Said shaft 38 has secured thereto a gear 40 which meshes with the gear 41 secured to the bottom shaft 42 of the loom, said gears 40 and 41 being of any desired ratio to produce the type of fabric desired. As shown herein the gears are so proportioned as to produce one rotation of shaft 38 for every rotation and a half of shaft 42, the shaft 42 receiving one rotation for every two picks of the loom, so that said shaft 38 makes a complete revolution every three picks. If so-called four-pick terry is desired the gears 40 and 41 can be chosen of such proportion as to make stub shaft 38 rotate twice as fast as the bottom shaft 42.

The cam 37 is shown more particularly in Figs. 7 and 8 and comprises a plate 43 from which projects an inner cam face 44 and a

flange 45. The flange extends only part way around the cam and defines with the inner surface 44 a track 46 proportioned to receive the roll 36. The distance from the 5 shaft 38 to the highest part of the face 44 is greater than the distance from said shaft to any part of the flange 45 to permit the roll 36 to remain in raised position without being engaged by the cam 37 as the latter 10 rotates.

For controlling the position of lever 29 I associate with the usual pattern mechanism a lever 47 pivoted as at 48 to a fixed support and cooperating with a pattern 15 chain 49. A lock 50 pivoted as at 51 to some fixed part of the frame has a notch 52 which cooperates with a boss 53 on the lever 29 and serves to hold said lever 29 in forward position when the pattern lever 47 is 20 down but releases said lever 29 when the lever 47 is raised. A spring 54 interposed between lever 26 and a fixed part of the loom frame tends normally to move the lever 29 rearwardly against the lock 50 and a spring 25 55 interposed between arm 32 and lever 35 serves to hold the lug 34 against the stop screw 32^a.

The full lines in Fig. 1 show the parts as 30 they will be placed when weaving a heading between sections of terry fabric. In this position the lock 50 holds the lever 29 in forward position against the action of spring 54 to hold the guide bar 18 and whip roll 17 in rear position with the fell of the cloth 35 so placed as to be engaged by the reed when the lay is in its forward position. In this position the lever 35 and roll 36 will be held in raised position. As the weaving of the heading is finished a ball 56 on pattern 40 chain 49 will be moved under the lever 47 to raise the same to the dotted line position and at the same time the highest part of face 44 will raise roll 36 slightly to relieve the pressure between boss 53 and lock 50. Lever 45 47 will raise link 57 connected to lock 50 to lift the latter out of the path of boss 53. Lever 47 will remain in raised position so long as terry fabric is being woven, this result being accomplished either by stopping 50 the pattern chain 49 or by providing the same with a plurality of rolls 56, the method of holding the lever 49 in raised position forming no part of the present invention and being well understood in the art.

55 As long as lock 50 is raised spring 54 will act to hold roll 36 against cam face 44. As the shaft 38 continues to rotate the roll 36 will move down along face 44 and pass into the track 46, being moved positively to the lowest part of the cam face 44 and requiring cam 29 to move rearwardly to the same position every third pick resulting in the forward movement of the guide bar 18 to the same position while the terry forming picks are being laid. As shaft 38 continues

to rotate and the roll 36 moves out of the track 46 said roll will be raised positively by the face 44 to move the guide bar 18 rearwardly to pile forming position.

If the length of pile is to be changed the 70 screw 33^a may be altered so that more or less lost motion may exist between said screw and the lug 34, the lever 35 always receiving enough motion to form the maximum height of pile. 75

In Figs. 3 to 6 inclusive I have shown the manner in which the pile is formed. With the roll 18 in forward position the fell of the cloth F will be forward and the shuttle will lay a pick of filling P some distance 80 to the rear of the fell of the cloth F as shown in Fig. 3. A second pick is then laid as shown in Fig. 4, and then a third pick P² is laid as in Fig. 5. On the beat of the lay corresponding to pick P² the roll 36 will be 85 moved to its highest position by the cam face 44 thus carrying the fell of the fabric F to the rear position shown in Fig. 6 to cause looping of the pile warp W^p intervening between the fabric and the pick P. 90

The pile warp W^p from the beam 17 moves forwardly with the ground warp by means of a roll 58 slidably mounted in an arm 59 and held rearwardly in said arm by means of spring 60 guided by a rod 61 in the arm 95 59. Said arm 59 is pivotally mounted as at 62 to another arm 63 secured to the shaft 17. By means of this construction the pile warp is moved back and forth at the same time that the ground warp is moved. 100

It is necessary to return the guide bar 18 to the same forward position in order to insure a uniform height of pile. Should said bar move varying distances from its rear position there would be a corresponding variation in the height of the pile and a consequent wavy appearance of the finished cloth. The structure set forth herein provides for returning the cloth to the same forward position and will therefore produce a fabric 110 free from wavy and irregular rows of pile loops. 110

From the foregoing it will be seen that I have provided means for moving the fabric positively in both directions toward and from terry pile forming position and that the lay and the reed carried thereby may be moved through a fixed range of action to permit the same to be of the substantial construction necessary when weaving high pile. 115 Also, it will be seen that when the loom is weaving a heading the lock 50 will serve to hold the fell of the cloth positively in rearward position and that the position of the said lock with respect to the boss 53 may be adjusted by means of screw 32^a. Furthermore, it will be seen that by adjustment of screw 33^a the height of the pile may be varied, spring 55 serving normally to hold the lug 34 against the screw 32^a to prevent 120 the lug 34 against the screw 32^a to prevent 125 the lug 34 against the screw 32^a to prevent 130

undue vibration. It will be further noted that the boss 53 and lock 50 remain unchanged when the parts are given a different setting to vary the height of the pile 5 and the boss is moved slightly away from the lock to permit the latter to be raised easily by the pattern lever 47.

Having thus described my invention it will be apparent that changes and modifications may be made therein by those skilled 10 in the art without departing from the spirit and scope of the invention and I do not wish to be limited to the details herein disclosed, but what I claim is:

15 1. In a terry pile fabric loom having a lay moving through a fixed range of action, a cam, a cam lever, said cam having a grooved portion to actuate the lever positively during a portion of the rotation of 20 the cam and having also a portion to move the lever positively in one direction only, means to hold the lever in raised position when the same is in position to be actuated by the second mentioned portion of the cam, 25 and connections between said lever and the fabric to move the latter toward and from pile forming position.

2. In a terry pile fabric loom having a lay moving through a fixed range of action, 30 a cam lever, a cam having a surface to actuate the cam lever, a portion of said surface effective to actuate said cam lever positively in two directions and another portion of said cam effective to actuate the lever positively 35 in one direction only, means to hold the lever in position out of the path of the first named portion of the cam, and means between said lever and the fabric to move the latter toward and from pile forming position.

40 3. In a terry pile fabric loom having a lay moving through a fixed range of action, a lever, connections between the lever and the fabric to move the latter toward and from pile forming position as the lever is moved, a cam to cooperate with the lever, said cam being formed in part as a track cam and in part as a face cam, the face cam being proportioned to move the lever to a 45 position to clear the track portion of the cam, and means to hold said lever in raised 50 position.

4. In a terry pile fabric loom having a lay moving through a fixed range of action, 55 means to support the cloth for movement

toward and from the lay, pattern mechanism, locking means to hold said supporting means in fixed position when a heading is being woven, mechanism to give said means a slight motion away from the lock at periodic intervals, connections from the pattern mechanism to move said locking means to unlocking position when said supporting means is moved slightly away from the lock. 60

5. In a terry pile fabric loom having a lay 65 moving through a fixed range of action, means to support the fabric, a driving lever having a fixed amplitude of motion, a driven lever operatively connected to said supporting means, a lock for said driven lever, adjustable connections between the levers to vary the position of the driven lever with respect to the lock and moving said driven lever positively in one direction, and adjustable connections between said levers to vary 70 the extent of motion of the driven lever and moving the latter positively in the opposite direction.

6. In a terry pile fabric loom having a lay, a regularly moving driving member, a 80 driven member, means operatively connected to the driven member to move the fabric relatively to the lay, connecting means between the members effective to cause positive movement of the driven member by the driving member in opposite directions by a portion of the driving member, said connecting means being effective to cause positive motion of the driven member in one direction only by another portion of said driving member. 85

7. In a terry pile fabric loom having a lay, a regularly moving driving member, a driven member, means operatively connected to the driven member to move the fabric relatively to the lay, connecting means between the members effective to cause positive movement of the driven member by the driving member in opposite directions by a portion of the driving member, said connecting means being effective to cause positive motion of the driven member in one direction only by another portion of said driving member. 95

In testimony whereof I have hereunto affixed my signature.

AUGUSTIN J. CHEVRETTE.
